IVAN A. McCARTHY, OF VANCOUVER, BRITISH COLUMBIA, CANADA.

ROTARY ENGINE.

1,193,808.

Specification of Letters Patent.

Patented Aug. 8, 1916.

Application filed March 27, 1915. Serial No. 17,353.

To all whom it may concern:

Be it known that I, IVAN A. McCARTHY, a citizen of the Dominion of Canada, residing at Vancouver, in the Province of British Columbia, Canada, have invented certain new and useful Improvements in Rotary Engines, of which the following is a specification.

This invention relates to an internal combustion rotary engine.

It belongs to that class wherein a driving head having vanes or bars projecting radially from it and parallel to its axis is secured on a driving shaft and is rotatable within a substantially concentric fixed cylinder, the bore of which is swept by the vanes of the driving head.

The concentric space between the driving head and its containing cylinder is divided into two compartments by valve members which are rotatable to permit passage of the vanes of the driving head.

The concentric space between the driving head and its containing cylinder is divided into two compartments by valve members which are rotatable to permit passage of the vanes of the driving head.

The invention comprises the arrangement of the described parts with the required ports and passages by which the explosive mixture may be delivered into one end of the hollow driving head, may pass therefrom into one compartment of the annular space, being drawn therein by the movement of one of the vanes through it. In this compartment the charge is compressed against the valve partition of the compartment by the next vane following and after compression passes into the next compartment of the annular space where it is ignited, the force of the explosion acting to rotate the driving head on the opposite side of the same vane which compresses the charge.

The compartment in which the explosion has occurred is then opened to the exhaust and movement of the next vane following sweeps the residue of the explosion from the compartment. As one vane of the driving head effects the compression of the charge in both compartments of the cylinder and receives the force of their explosions, it may be termed the power vane, and the other, which indraws the charge and scavenges each compartment, is termed the

suction and scavenging vane. As a charge is compressed into and exploded in each compartment the engine receives two rotative impulses in each revolution.

The engine and its manner of operating is fully described in the following specification, reference being made to the drawings by which it is accompanied, in which:

Figure 1 is a longitudinal section of the engine on the line *b*—*b* in Fig. 2. Fig. 2 is a cross section on the line *a*—*a* in Fig. 1, that is, through the gas intake compartment of the driving head. Fig. 3 is a cross section on the line *k*—*k* in Fig. 1, that is, through the exhaust compartment of the driving head. Fig. 4 is a section on the line *c*—*c* in Fig. 2 or 3. Fig. 5 is an end view of the intake end of the engine, a portion of the end cover being removed to show the partition valve driving gears. Fig. 6 is a cross section on the line *d*—*d* in Fig. 1 showing the ports of the extension of the partition valves, and in elevation the exhaust delivery from the engine. Fig. 7 is a section on the line *e*—*e* in Fig. 6, being through one of the partition valves in a plane parallel to the port delivering to one of the annular working compartments of the engine. Figs. 8, 10 and 12 are cross sections through the engine cylinder and partition valves showing the cycle of operation of the engine, and Figs. 9, 11 and 13 are cross sections through the partition valve extensions respectively corresponding to the foregoing Figs. 8, 10 and 12.

In these drawings 2 represents a driving shaft on which is secured a hollow cylindrical driving head 3, the hollow of which is divided into two parts 5 and 6 by a partition 4, which also provides the means for attachment of the driving head 3 on the shaft by a feather or key. On the periphery of this driving head 3 vanes 8 and 9 are secured parallel to the axis of rotation.

The driving head 3 with its vanes is rotatably mounted within a cylinder 7, the ends of which, (see Fig. 4) are bored to receive the ends of the driving head, while the vanes 8 and 9 closely fit and sweep the concentric space 10, 11 between the driving head and the bore of the cylinder. This concentric space is divided into two diametrically opposite compartments 10 and 11 by partition valves 12 and 13 which are rotatable at

twice the speed of the driving head in valve seats which are stepped at one end into the end of the cylinder 7, (see Fig. 1). Each seat is bored in an enlargement across the 5 width of the cylinder and within a cylindrical projection 19 beyond the other end. The cylindrical projection 19 of each valve seat or chamber is closed with a plug cover 21 which is threaded to receive an ignition 10 plug. A port 18 extends along practically the entire length of each valve chamber or seat and connects that portion of it that extends along the cylinder 7 with that portion 15 19 which projects beyond the end of the same; and a port 20 connects the projecting portion 19 of the valve seat, (see Fig. 7) with concentric compartments 10 and 11 respectively, delivering into them toward the direction of rotation of the 20 engine.

The partition valves 12 and 13 which are rotatable within these seats have a general diameter which is substantially half that of the driving head 3 and is greater than the 25 radial dimension of the concentric chamber 10, 11 between the driving head 3 and the bore of the cylinder 7. That portion of each valve, which is within the sweep of the vanes 8 and 9 is chambered or hollowed 30 out, as at 14, and 15, to permit passage of the vanes as the driving head rotates and the faces of the vanes where they engage the inside of this chambered recess are shaped to contact as far as practicable therewith 35 during rotation, except in the vane 8 adjacent the admission and exhaust ports.

That portion of each partition valve, which is extended beyond the length of the cylinder 7, is hollow as at 16, and has a port 40 17, the middle line of which is in approximate alignment with the leading horn of the crescent of that portion of the valve which lies within the sweep of the vanes.

During rotation of either valve the port 45 17 of its hollow extension registers with the port 18 of its seat and so connects the cavity 14 or 15 of the valve with the hollow 16 of its extension, and on further rotation the same port 17 connects the hollow 16 of the 50 valve with the port 20 delivering into the concentric chamber 10 or 11, as the case may be.

The valves 12 and 13 are rotated co-operatively with the driving head 3 and at 55 twice the speed, by a gear wheel 30 which is integral with or secured to the outer end of the driving head, and the teeth of this gear wheel mesh with those of a smaller wheel secured on the stepped or shouldered 60 end of each valve 12 and 13. The valves rotating at twice the speed of the head will present their hollowed out portions 14 or 15 to each vane as it approaches, and will turn with it to pass the vane to the other 65 side of the partition valve.

The gear wheels are inclosed by a cover 22 which closes also the open end of the admission compartment 5 of the hollow driving head, and the ends of the valves 12 and 13. This cover 22 has a hub 23 which projects into the chamber 5 and forms a bearing to support the driving shaft 2. The driving shaft is supported on the other end of the cylinder by a bearing which forms a hub on the cover plate 24.

The explosive mixture of gas and air is delivered from the carburetor into the compartment 5 of the hollow driving head 3 through an aperture 25 in the end cover 22, and passes therefrom into the compartment 70 10 or 11 through a port 26 in the driving head, which port is adjacent the following 75 side of the vane 8, which may be called the suction and scavenging vane.

The inner edge of the port 26 projects 85 slightly into the chamber 5, and admission through this port is controlled by the movement of it past enlargements 29 projecting from the bearing hub 23, which enlargements are diametrically opposite one another. The reason for this control will be explained later. On the opposite or leading 90 side of this same vane 8 a port 27 connects either chamber 10 or 11 with the compartment 6 of the hollow driving head, which 95 compartment of the driving head is in connection with the exhaust of the engine through apertures 28 in the cover 24 of the cylinder, that is, on the opposite end of the cylinder to that to which the carburetor is 100 connected at 25.

During rotation, in the direction of the arrow, of the driving head 3 with its vanes 8 and 9 within the cylinder 7, which is stationary, the movement of the suction vane 8, (see Fig. 8) from the partition valve 12, induces a flow of gas and air from the carburetor through the hollow end 5 of the driving head, and through the port 26 into the compartment 10 of the cylinder, and when the 105 vane 8 has passed the valve 13, which valve is turning with the driving head to present its hollow 15 to the passing vane, the compressing and power vane 9 has simultaneously passed the other valve 12, and the in-taken charge of gas and air is compressed, by movement of the vane 9 toward the valve 13, which by this time is closed, (see Fig. 10). As the vane 9 approaches the valve 13 (see Fig. 10) the charge compressed within 110 the compartment 10 passes through the ports 18 and 17 into the hollow end 16 of that valve prolongation, (see Fig. 11). When the vane 9 has passed the valve 13, (see Fig. 12) that valve has turned, (see Fig. 13) to 115 connect the port 17 of its hollow prolongation 16, with the port 20 delivering into the compartment 11 on the other side of the valve 13. When this communication 17, 20 is open to the compartment 10 or 11, the 120 130

compressed charge is ignited by the ignition plug 23 of this valve and the force of the explosion acts against the following sides of the vane 9 to rotate the driving head and its shaft, as indicated.

When, under the force of the explosion the vane 9 has been moved to the position indicated in Fig. 8, movement of the suction vane 8 past the valve 13, uncovers the exhaust port 27 and the products of the explosion are free to pass through that port, and through the compartment 6 of the driving head to the exhaust through the outlets 28. Further movement of the suction and scavenging vane 8 through the compartment 11 sweeps the residuum of the explosion through the port 27 as the vane moves toward the closed valve 12, (see Fig. 10).

It will be observed that there are two operations of suction, two of compression, two explosions and two operations of scavenging, during each revolution of the engine, one within each compartment 10 and 11.

The suction of the new charge into the compartment 11 and the scavenging of the products of the last explosion from that compartment occur as the vane 8 moves from the valve 13 to the valve 12 and the same while the same vane passes through the compartment 10 from the valve 12 to the valve 13.

The compression of the charge indrawn to the compartment 10 occurs as the vane 9 passes from the valve 12 to the valve 13 and 35 the charge compressed in the compartment 10 is delivered from that compartment to the compartment 11 as the vane 9 passes the valve 13; while the charge compressed in the compartment 11 is delivered from that 40 compartment to the compartment 10 as the vane 9 passes the valve 12, the explosion of each charge occurring immediately after the vane 9 has passed the valves 12 and 13 respectively, at which time the port 17 has established communication through the passage 20 with the following side of the vane 9 in the next compartment in advance.

The provision of the enlargements 29 on the bearing hub 23 are designed to close the 50 port 26 to prevent any leakage of compressed gas past either valve 12 or 13 causing a back blow through the carburetor.

The vanes 8 and 9 will be packed to closely fit their bearings in the bore of the cylinder 7 and at the end of the annular space, and the valves 12 and 13 will tightly fit their bearings in the cylinder 7 and against their rolling contact on the driving head. They may have a conical taper to insure such fit. The valves 12 and 13 being of larger diameter than the radial dimension of the uniform chamber which they separate into compartments will have a satisfactory bearing on their seats in the cylinder 7 to 60 withstand the force of the explosion, the

pressure of which will tend to close them tightly on both contacts.

The charge being ignited in the hollow end 16 of each valve the valves are shoudered at the opposite end in the end of the 70 cylinder 7 to withstand that endwise pressure of the explosion and it will be noted that the friction of the valves on their seats between the driving head and the cylinder, due to the pressure of the explosion against 75 them, will relieve to a great extent the endwise pressure on the shoulder of the valve itself.

While every care will be taken to see that the faces of the vanes 8 and 9 closely fit at 80 their contact in the hollows 14 and 15 of the valves, attention is drawn to the fact that while difficulty may be experienced in making these parts practically gas-tight, leakage past them during compression and explosion will not constitute a loss seriously 85 detrimental to the efficiency of the engine; for while the vane 9 is passing either valve 12 or 13 the compartment in advance of it on the other side of the valve is indrawing a 90 fresh charge and any leakage of compressed gas will not therefore be lost but will be utilized for the next explosion. Nor will there be much tendency to leakage from the compression side of the vane 9 to the opposite 95 or power side, as the residuum of the compressed gas, after the greater part of it has been delivered into the hollow end 16 of the valve, will not be much in excess of the residuum of the products of combustion after 100 the exhaust port has opened, which will be the case as the vane 9 is passing the valve.

Having now particularly described my invention, I hereby declare that what I claim as new and desire to be protected in 105 by Letters Patent, is:

1. In a rotary engine, the combination with a hollow cylindrical driving head in which the driving shaft of the engine is secured, said driving head having a power 110 vane and a suction vane projecting from diametrically opposite sides of its circumferential surface, a cylinder within which said driving head and its vanes is rotatable, said driving head and its vanes being rotatably mounted in the cylinder in contact with the driving head at diametrically opposite sides 115 dividing the annular space swept by the vanes into two compartments the diameter of said valves being substantially half that of the driving head and each valve hollowed on one side to permit passage of the vanes as they 120 rotate, means for delivering a gaseous fuel into one compartment of the annular space surrounding the driving head, and means controlled by the movement of the valves for 125 passing the indrawn gas into a chamber in 130

the produced end of each valve for subsequent delivery into the compartment of the cylinder in advance of each valve.

2. In a rotary engine, the combination 5 with a hollow cylindrical driving head in which the driving shaft of the engine is secured, said driving head having a power vane and a suction vane projecting from diametrically opposite sides of its circumferential surface, a cylinder within which said driving head and its vanes is rotatable, said cylinder having ends which close the ends of the space between the circumference of the driving head and that of the cylinder 10 swept by its vanes, partition valves rotatably mounted in the cylinder in contact with the driving head at diametrically opposite sides dividing the annular space swept by the vanes into two compartments 15 the diameter of said valves being substantially half that of the driving head and each valve hollowed on one side to permit passage of the vanes as they rotate and having a ported chamber in a produced end of the 20 valve produced beyond the end of the cylinder which port is connected by a passage in the valve seat to one compartment of the cylinder and by a port in the produced seat to the other compartment.
3. In a rotary engine, the combination 25 with a hollow cylindrical driving head in which the driving shaft of the engine is secured, said driving head having a cross partition dividing it lengthwise into two compartments, said driving head having also a power vane and a suction vane and a port from one compartment of the driving head alongside the following side of the suction vane and a port from the leading side of the 30 same vane delivering into the other compartment of the driving head, a cylinder within which said driving head with its vanes is rotatable, said cylinder having ends which close the ends of the space between the circumference of the driving head and that of the cylinder 35 swept by its vanes, partition valves rotatably mounted in the cylinder in contact with the driving head at diametrically opposite sides and dividing the annular 40 space swept by the vanes into two compartments, said valves adapted to permit passage of the vanes as they rotate, means for delivering a gaseous fuel into the compartment of the driving head which is connected 45 to the following side of the suction vane, means for passing the compressed gas from one compartment of the annular space of the cylinder to the other coincident with the movement of a vane past the valve, means 50 for igniting the compressed gas so delivered, and means for exhausting the products of combustion through the other compartment of the hollow driving head.
4. In a rotary engine, the combination 55 with a cylindrical driving head having driv-

ing vanes projecting from its outer cylindrical surface in which driving head the driving shaft of the engine is secured, a cylinder within which the driving head is concentrically mounted, said cylinder having ends which close the ends of the space between the circumference of the driving head and that of the cylinder swept by its vanes, partition valves rotatably mounted at diametrically opposite sides to divide the 70 annular space between the outer circumference of the driving head and the bore of the cylinder swept by its vanes, gearing external to the cylinder and coöperative with the driving head for driving the partition valves 75 at the required speed, a gear case for said gearing, means for delivering an explosive mixture of gas and air through the gear case of the partition valves to the compartments of the cylinder, means for igniting the 80 charge in these compartments, and means for exhausting the products of combustion 85 therefrom.

5. In a rotary engine, the combination 90 with a cylindrical driving head having driving vanes projecting from its outer cylindrical surface in which driving head the driving shaft of the engine is secured, a cylinder within which the driving head is concentrically mounted, said cylinder having ends 95 which close the ends of the space between the circumference of the driving head and that of the cylinder swept by its vanes, said cylinder having also valve seats recessed from its inner circumferential surface at diametrically opposite sides, partition valves 100 rotatably mounted in these seats and in rolling contact with the circumferential surface of the driving head, said valves being shouldered at one end to a less diameter to pass 105 through one end of the cylinder and having gear teeth on the outwardly projecting end, which teeth mesh with others on the outer end of the driving head the pitch diameters of these teeth being respectively proportioned to drive the valves at twice the rotation of the head, a cover inclosing the gears of the driving head and valves, means for delivering an explosive mixture to within 110 this casing, means for admitting it to the compartments of the cylinder swept by the vanes of the driving head, means for igniting the charge, and means for delivering the products of combustion from the compartments.

6. In a rotary engine, the combination 115 with a hollow cylindrical driving head in which the driving shaft of the engine is secured, said driving head having a cross partition dividing it lengthwise into two compartments and having also a power vane and a suction vane, and a port from one compartment of the driving head adjacent the following side of the suction vane, and a port from the leading side of the same vane 120 125 130

delivering into the other compartment of the driving head, a cylinder within which said driving head with its vanes is rotatable, said cylinder having ends which close the ends of the space between the circumference of the driving head and that of the cylinder swept by its vanes, partition valves rotatably mounted in the cylinder at diametrically opposite sides and dividing the annular space 5 swept by the vanes into two compartments, means for delivering a gaseous fuel into the compartment of the hollow driving head which is connected to the following side of the suction vane, means connected to the cyl- 10 inder which is stationary for controlling 15 the passage of the gaseous fuel through the port delivering into the compartments of the concentric space, means for igniting the charge to act on one of the vanes in the concentric space, and means for exhausting the products of combustion through the other compartment of the hollow driving head. 20

In testimony whereof I affix my signature in presence of two witnesses.
